UNITED STATES PATENT OFFICE

PIERRE JEAN RENÉ POSTEL-VINAY, OF PARIS, FRANCE, ASSIGNOR TO SOCIETE DES
MOTEURS SALMSON, (SYSTEME CANTON-UNNE,) OF PARIS, FRANCE.

WOOD-SLICING MACHINE.

1,415,470.

Specification of Letters Patent.

Patented May 9, 1922.

Application filed June 24, 1921. Serial No. 480,184.

To all whom it may concern:

Be it known that I, PIERRE JEAN RENÉ POSTEL-VINAY, citizen of the French Republic, residing at Paris, in the Republic of France, have invented new and useful Improvements in Wood-Slicing Machines, of which the following is a specification.

In machines which make use of a knife for cutting the material, such for instance as in slicing machines for veneer wood, the knife is frequently disposed obliquely with reference to the path of the tool-holder. This arrangement facilitates the slicing according as the obliquity is greater. But the use of a too great angle gives rise to a side thrust which is prejudicial to the framework of the machine and likewise requires a longer stroke for the knife-holder in order to cover the whole surface of the rectangle formed by the log.

The herein described arrangement which provides for a cross motion of the knife-holder will obviate these two drawbacks.

The accompanying drawing shows by way of example an embodiment of this invention.

Fig. 1 is an elevational view of a slicing machine with cross-motion according to this invention.

Fig. 2 is a corresponding plan view of the same.

Fig. 3 is a sectional view of the same on a larger scale, on the line A—A Fig. 1.

The knife C (Figs. 1 and 2) is mounted on the knife-holder P which is in turn secured to the slide D, adapted to slide in a transverse direction on the carriage E. The carriage E is given a reciprocating motion in the longitudinal direction of the machine by means of the racks K secured thereto and the pinions N of the shaft M actuated by a known speed reducing and reversing device with limited and adjustable stroke. The slide D is provided with a rack H engaging the pinion I of a shaft R which rotates in a bracket secured to the carriage E, the said shaft being provided at the lower end with a pinion S engaging a rack T. The rack T is slidable lengthwise of the machine with a small stroke, and the ends thereof are adapted to enter in contact at the end of the stroke with the adjustable spring stop pieces U, U'.

The operation of this machine is as follows:

Upon starting the stroke towards the ma-

terial to be sliced, the carriage E moves forwardly and thereby draws with it the shaft R, the pinion S and the rack T whose inertia against sliding motion is less than that of the slide D. At the end of the stroke X—U¹ of the said rack, the rear end thereof will enter in contact with the stop-piece U¹. Inasmuch as the shaft R continues its forward motion together with the carriage, the pinion S is obliged to rotate together with the pinion I which by means of the rack H causes the slide D to assume a sidewise movement as shown by the arrow 1 (Fig. 2). Like movements but in the inverse sense are effected on the return stroke of the knife.

If the line OV (Fig. 2) perpendicular to the knife is inclined by an angle α to the direction OY of lengthwise movement; the reaction of the sliced material will take a direction approximating this perpendicular, whereby the framework of the machine will be subjected to a thrust which is equal and opposite to the effort OF, for instance. But the cross-motion in the direction OZ will require an effort OG exactly opposite to the effort OF and susceptible of reducing this latter to an advantageous degree, should the dimensions be suitably chosen. From the combination of the two movements OY and OZ it will furthermore result that the elements of the knife will assume an effective direction OW which makes a considerable angle, $c = a \times b$, with the edge of the knife, this being very favorable to the cut.

If it is desired for any reason to stop the cross-motion of the knife, such as in the case of thin cuts, the pinion S (Fig. 3) is rendered loose on the shaft R by raising the clutch member 3 which then engages a fixed tappet J and thus prevents further rotation of the shaft R the pinion S rotating idly under the action of the rack T in the operation of the machine.

Having now described my invention I declare that what I claim and desire to secure by Letters Patent is:

1. A wood slicing machine comprising a frame, a reciprocating carriage on said frame, means for operating said carriage, a slide, means for guiding said slide on the carriage in a direction at an angle with the direction of travel of the carriage, a tool-holder on said slide, a cutter on said tool-holder having its cutting edge at an angle with the said direction of travel, a shaft

rotatably supported on said carriage, two pinions on said shaft, a rack secured to the slide and in engagement with one of said pinions, a rack slidably mounted on the machine frame and in engagement with the other pinion and stop members on the machine frame for limiting the stroke of the latter rack.

2. A wood slicing machine comprising a frame, a reciprocating carriage on said frame, means for operating said carriage, a slide, means for guiding said slide on the carriage in a direction at an angle with the direction of travel of the carriage, a tool-

holder on said slide, a cutter on said tool-holder having its cutting edge at an angle with the said direction of travel, a shaft rotatably supported on said carriage, two pinions on said shaft, a rack secured to the slide and in engagement with one of said pinions, a rack supported on the machine frame and in engagement with the other pinion and a clutch adapted to disengage the latter pinion from the said shaft and to prevent rotation of said shaft.

In testimony whereof I have signed my name to this specification.

PIERRE JEAN RENÉ POSTEL-VINAY.
